UNITED STATES PATENT OFFICE

130,778

DESIGN FOR A POCKET KNIFE OR SIMILAR ARTICLE

Felix A. Mirando, Providence, R. I.

Application March 19, 1941, Serial No. 99,696

Term of patent 14 years

To all whom it may concern:

Be it known that Felix A. Mirando, a citizen of the United States and resident of Providence, in the county of Providence and State of Rhode Island, has invented a new, original, and ornamental Design for a Pocket Knife or Similar Article, of which the following is a specification, reference being had to the accompanying drawing, forming part thereof, in which,

Fig. 1 is a top view of a pocket knife embodying my new design;

Fig. 2 is a side view thereof; and
Fig. 3 is an end view thereof.

I claim:

The ornamental design for a pocket knife or similar article, substantially as shown.

FELIX A. MIRANDO.
